UNITED STATES PATENT OFFICE.

ELVIRA BAKER, OF MITCHELL, INDIANA.

DRESS-MAKER'S CHART.

SPECIFICATION forming part of Letters Patent No. 349,198, dated September 14, 1886.

Application filed February 11, 1884. Renewed July 1, 1886. Serial No. 206,862. (No model.)

To all whom it may concern:

Be it known that I, ELVIRA BAKER, a citizen of the United States, residing at Mitchell, in the county of Lawrence and State of Indiana, have invented certain new and useful Improvements in Dress-Makers' Charts; and I do declare the following to be a full, clear, and exact description of the invention, such as will enable others skilled in the art to which it appertains to make and use the same, reference being had to the accompanying drawing, and to letters or figures of reference marked thereon, which form a part of this specification.

The figure of the drawing is a representation of this invention.

The drawing shows a plan view of the invention.

This invention has relation to combined pattern guides or charts and scales for dress-makers' use; and it consists in the construction and novel arrangement of devices constituting the dress-maker's chart and scale in one piece, as hereinafter set forth, and pointed out in the appended claim.

In the accompanying drawing, the letter A designates the combined chart and scale, which may be made of stout paper, stiffened cloth, or other suitable material. On one side is the long straight margin B, and at the bottom 30 a shorter straight edge, C, at right angles to the straight edge B. At the top adjoining the straight edge B is a short slightly curved edge, D, forming the back-neck guide from which curved shoulder-guide edge E, extends obliquely to the long curved edge F, which is on the opposite side of the chart from the straight edge B, and extends to the short straight edge C, as shown.

G indicates a long oblique curved slot having its margins meeting in a point at the lower end. Its concave margin H is on the side of the long straight edge B, and its convex margin I is on the side of the curved edge F. Near the upper end of this slot is a short curved slot, K, extending transversely and having its convex margin L on the lower side and its concave margin N on the upper side. Along the straight edge B is marked a scale of inches and parts of inches. This 50 is a compound scale having a row of figures at the edge to serve as the front-neck scale, a, and a row of figures back of the same to serve as the front-bust scale b. On the short

straight edge C is marked the back-waist scale c. Along the long curved edge F is marked the front-waist scale d, and this edge forms at its upper part the back-arm guide e. A scale, f, is marked along the shoulder-guide edge E. The concave edge N of the transverse curved slot K serves for the arm-scye guide, as at h, and for the front-neck guide, as at k. The front or concave edge of the long oblique slot is marked with a scale, g, and it serves as the side-body guide. The back or concave edge of this slot, also marked with a scale, l, serves as the under-arm guide. These curved inner margins meet in a point at the lower end, and together serve as the dart-guide n, as shown.

Perforated scales are provided as follows: 70 The front-shoulder scales p and z, extending, respectively, from the rear curved edge F upward and obliquely forward and from the bottom straight edge upward and slightly forward. From the upper part of the long 75 curved edge F, inward and upward transversely extends the scale r, by which the front-bust line is located. The back-shoulder scales s and t extend, respectively, from the rear end of the back-neck guide D, at the top 80 downward and obliquely forward toward the front straight edge, B, and from the upper end of the back curved edge, F, transversely downward and inward toward the inner convex edge of the long slot. The transverse perforated scale v extends from the middle portion of the long curved edge F inward, as shown, and forms the back-bust scale.

Having described this invention, what I claim, and desire to secure by Letters Patent, 90 is—

A dress-maker's chart and guide formed in one piece, and having the external straight edges B C, the upper curved edge, D, the oblique-curved edge E, the vertically-curved edge F, the upper transversely-curved slotted portion K, and the vertically-slotted portion G, having edge scale-marks, and the whole provided with scales for the various curved and straight edges, substantially as specified. 100

In testimony whereof I affix my signature in presence of two witnesses.

ELVIRA BAKER.
